COMBINATION HACK AND COMPASS SAW
FRAME

Joseph M. Up De Graff, Peoria, Ill.

Application June 17, 1937, Serial No. 148,802

3 Claims. (Cl. 145—31)

This invention relates to an improved hack and compass saw frame intended to prevent the usual hack and compass saw blade from buckling and breaking in the work.

It has been customary to mount such blades in U-shaped frames with the blade secured at each end. The intermediate portion of the blade is unsupported so that it can easily bend, twist or buckle resulting in a possible broken blade.

10 The invention is intended to produce a frame wherein the greater portion of the blade is held against bending and buckling and where the frame is always engaging the blade close to the point at which the blade is actually cutting.

15 This is accomplished by slidably mounting the blade in a slotted bar so that the bar can constantly engage the work to form a guide for the blade as it reciprocates.

A further object of the invention is to provide 20 means to continuously hold one end of the bar in engagement with the work.

Other objects and advantages of the invention will hereafter become more apparent from the specification of which the drawings form a part, 25 and wherein:

Figure 1 is a side elevational view of the invention;

Figure 2 is an enlarged fragmentary longitudinal vertical sectional view partly in elevation 30 of the same;

Figure 3 is an enlarged cross sectional view on the line 3—3 of Figure 1;

Figure 4 is an enlarged cross sectional view on the line 4—4 of Figure 1;

35 Figure 5 is an enlarged cross sectional view on the line 5—5 of Figure 1;

Figure 6 is an enlarged horizontal sectional view on the line 6—6 of Figure 1;

Figure 7 is an enlarged horizontal sectional 40 view on the line 7—7 of Figure 1; and

Figure 8 is a fragmentary view in elevation partly broken away showing the recess in one end of the bar to receive the roller bearing.

Referring more particularly to the drawings 45 wherein like reference characters designate like or corresponding parts in the different views, 10 designates generally the improved saw frame comprising a handle 11 formed of the sections 12 and 13 secured together by means of a stud 14 and a screw 15. In the upper part of portion 12 is formed a bore 16 in which is slidably mounted a bar 17.

Secured to the top of handle 11 by a threaded bolt 18 is a knob or handle 19. Secured along 50 one side of handle 11 on a plane with bore 16 is

a barrel 20 which is held in place by the screws 21 and 22. Barrel 20 houses coil spring 23 which has one end connected to screw 21 and the opposite end to a bracket 24 mounted on a threaded bolt 25 which engages an opening in end 26 of 5 bar 17.

Bar 17 is provided with an elongated slot 27 shaped to receive a saw blade 28 which is clamped at one end between the parts 12 and 13 of the handle 11.

Secured to the end 29 of bar 17 is a collar 30 provided with a slot 31 in the bottom thereof to accommodate blade 28. Extending downwardly from collar 30 is a stop 31 adapted to bear against one side of the material to be cut. 10

Extending up from and formed integral with collar 30 is a standard 32 provided with an offset portion 33 on which is mounted a knob 34 by means of a threaded bolt 35 which extends through into a threaded opening in portion 33. 20

Secured in the collar 30 is a shaft 36 provided with a reduced threaded end 50 to engage the internally threaded insert 51 mounted in opening 52 of collar 30. On shaft 36 is mounted a bearing 37 which revolves in a recess 38 in standard 25 32 and in a recess 39 in the end 29. End 29 is also provided with an arcuate recess 40 to accommodate a portion of shaft 36.

Bearing 37 extends down sufficiently to engage the back edge of blade 28 as best seen in Figure 5 30 so that the blade 28 when in operation will ride on bearing 37 instead of binding against the top portion of slot 27 due to the pressure of blade 28 on the work.

Standard 32 is provided with a recess 41, as 35 best seen in Figure 7 in which is mounted a strip of thin steel 42 having one end bent at a right angle to form the portion 43. Also mounted in recess 41 is a wedge shaped clamp 44 provided at its larger end with a portion 45 extending at a 40 right angle from the clamp portion 44. In the end of the portion 45 is a recess 46 to receive the shank of a threaded bolt 47 which engages a threaded opening 49 in the enlarged portion 48 extending from one side of the standard 32. 45

Strip 42 can be adjustably positioned in recess 41 and clamped by tightening bolt 47 to force the wedge 44 into a tight frictional engagement with strip 42 and with the sides of the recess 41.

Collar 30 and end 29 are provided with aligned 50 openings 53 to receive a pin 54 to key collar 30 to end 29 of bar 17 to prevent collar 30 from sliding on bar 17.

In operation, spring 23 and strip 42 are used alternatively. If the material is wide and thick 55

strip 42 is removed and spring 23 is relied upon to hold the stop 31 and the end 29 of bar 17 against the work. If the material is thin such as a sheet of metal to be sawed, the spring 23 is disconnected and strip 42 is positioned in the cut made by the blade with the turned end 43 bearing against the outer face of the material, to hold the inner face tight against stop 31 and end 29. Strip 42 is adjustable by means of the bolt 41 as heretofore explained to adjust the strip 42 to material of different thicknesses.

As heretofore explained, end 29 of bar 17 and stop 31 are held against the material by either the spring 22 or the strip 42, and the operator 15 grips the handle 11 in his right hand and either the knobs 19 or 34 in his left hand, to operate the saw. By pushing forward on handle 11, the blade 28 and the knob 19 carried by the handle 11, slide forward on bar 17 which is slidably mounted 20 in the bore 16 of the handle portion 12 to cause the exposed ends of blades 28 to cut the material. As the handle is pulled back again bore 16 slides 25 back over bar 17 which is held stationary either by the spring 23 or the strip 42. Pin 54 prevents the collar 30 from sliding on bar 17 when strip 42 is used. It can be seen therefore that the handle 11 is mounted to reciprocate on bar 17, and the blade 28 clamped in handle 11 as best seen in Figure 3, is reciprocated in slot 27 of the bar 17 30 to permit the exposed end of the blade 28 as it moves in and out of slot 27, to saw the material.

It is to be understood, that only the preferred embodiment of the invention has been shown and described, the right being reserved to make such 35 changes and modifications as do not depart from the spirit and scope of the invention as claimed.

I claim as my invention:—

1. A hack saw frame comprising a handle, a slotted bar slidably mounted therein, a blade secured in said handle and slidably mounted in said bar, a collar keyed to one end of said bar and having a stop formed integral therewith, and a metal strip adjustably mounted above said collar to extend through the cut in the work, the end 45 of said strip being bent to engage the work to

hold the collar in engagement therewith, the free end of the blade extending beyond said collar and bar to engage the work with the blade mounted to reciprocate in the slotted bar to saw the material.

2. A hack saw frame comprising a handle having a grip portion formed of connected sections and a bore arranged substantially at right angles thereto, a slotted bar slidably mounted in said bore, a blade clamped between the sections of the grip portion of said handle and slidably mounted in the slot of said bar, a collar mounted on the forward end of said bar and provided with a stop to engage one face of the material to be cut, a standard extending upwardly and rearwardly 15 from said collar, a knob mounted on said standard forming a second grip portion, and a metal strip adjustably mounted in said standard above and in a plane with said blade and projecting forwardly to extend through the cut in the material, the end of said strip being bent to engage against said material, said blade extending beyond said bar to engage the work with the stop and strip holding the frame in engagement with the work.

3. A hack saw comprising a frame including a bar having a longitudinal slot, a handle having a transverse bore to slidably engage said bar, the grip of said handle having a removable section adapted to cooperate with a stationary section 30 for clamping one end of a hack saw blade therein, said blade being slidably mounted in the slot of said bar with its opposite end extending beyond said bar to engage the material to be sawed; a standard secured to and projecting upwardly 35 from said bar, said standard being provided with a slot, a strip slidably mounted in said last mentioned slot and having one end bent to form a stop, and a wedge member for adjustably clamping said strip in the slot, said strip extending 40 through the cut in the material to dispose the stop on the far side thereof to retain the material in engagement with the bar.

JOSEPH M. UP DE GRAFF. 45
